UNITED STATES PATENT OFFICE

91,796

DESIGN FOR A SLED

Harold L. Van Doren and John G. Rideout, Toledo, Ohio, assignors to The American National Company, Toledo, Ohio, a corporation of Ohio

Application January 15, 1934, Serial No. 50,415

Term of patent 14 years

To all whom it may concern:

Be it known that we, HAROLD L. VAN DOREN and JOHN G. RIDEOUT, citizens of the United States of America, residing at Toledo, in the county of Lucas in the State of Ohio, have invented a new, original, and ornamental Design for a Sled, of which the following is a specification, reference being had therein to the accompanying drawing forming a part thereof, wherein:

Figure 1 is a top plan view of a sled;
Figure 2 is a side elevation thereof;
Figure 3 is a front elevation thereof.

We claim:

The ornamental design for a sled substantially as shown.

HAROLD L. VAN DOREN.
JOHN G. RIDEOUT.
